UNITED STATES PATENT OFFICE.

WILLIAM B. FOSTER, OF NORWOOD, AND THOMAS E. MANNING, OF CINCINNATI, OHIO.

SANITARY PASTE-DISPENSING DEVICE.

Application filed June 19, 1925. Serial No. 38,364.

To all whom it may concern:

Be it known that we, WILLIAM B. FOSTER and THOMAS E. MANNING, citizens of the United States, residing, respectively, in 5 Norwood and in Cincinnati, in the county of Hamilton and State of Ohio, have jointly invented certain new and useful Improvements in Sanitary Paste-Dispensing Devices, of which the following is a specification.

10 Our invention relates to sanitary paste dispensing devices for use in the home or other places for dispensing paste, such as tooth-paste, shaving paste and the like, and is exemplified as used in connection with 15 tooth-paste, it being understood that the paste is inclosed in tubes of usual form, so arranged that the paste may be exuded from the mouth of the tube by squeezing the tube.

It is the object of our invention to provide 20 novel means for supporting the paste-tube; further, to provide novel means for squeezing the tube in order to cause exuding of the paste therefrom; and, further, to provide 25 novel means for supporting the paste-tube and its manipulating devices; and the invention will be further readily understood from the following description and claims, and from the accompanying drawings, in which latter:

30 Fig. 1 is a plan view of our improved device.

Fig. 2 is a front view of the same, partly in section.

Fig. 3 is a side view of the same.

35 Fig. 4 is a horizontal section, taken on the line 4—4 of Fig. 2.

Fig. 5 is a vertical section, taken in the plane of the line 5—5 of Fig. 2; and

40 Fig. 6 is a vertical sectional detail, taken on the line 6—6 of Fig. 2.

Our improved device comprises a pair of guides 11, 12, respectively formed by rods 13, 14 and 15, 16. These guides are shown as hangers depending from a supporting plate 17, secured to said supporting plate by 45 riveting said rods thereto, as shown at 18.

The lower ends of the rods are connected by a plate 21, shown riveted to said plate, as at 22. The plate 21 is arranged to support 50 the paste-tube, shown at 23. This paste-tube, as is usual, comprises a breast 24, from which a threaded neck 25 extends.

The threaded neck has the mouth 26 of said tube at its outer end, the mouth being 55 normally closed by a cap 27, having an inner threaded bore 28 received over said threaded

neck, the end of the bore having a cushion-washer 29 therein for closing said mouth. The cap has an enlarged head 30, which may be readily grasped by the fingers, for screwing the cap on and off of the tube.

The body 31 of the tube is of flexible metal, as is usual, and the end of the tube is closed by a stiffer metal U-shaped clip 32, which is clamped over the end of the body 65 of the tube in usual manner for forming a butt-end for the tube.

The supporting plate 21 for the tube is provided with a downwardly dished-portion 33, in which the breast of the tube is arranged to rest, said downwardly dished portion having a central opening 34, through which the neck of the tube is received. This opening is of less diameter than the head 30 of the cap 27 of the tube, so that when the cap is on the tube, the tube is held endwise in both directions by the wall of said opening 34 between the breast 24 of the tube and said cap 27.

A rotary squeezer 41 is provided, which is 80 arranged to be connected with the butt-end of the tube in such manner that by rotation of the squeezer, the tube will be rolled about the squeezer, thereby squeezing the tube and causing the exuding of the paste through 85 the mouth of the tube.

This rotary squeezer is exemplified as formed out of a wire, the middle portion of which is bent in reverse directions for forming a handle 42, and forming shanks 43 90 parallel with each other, having a slot 44 between them, which is open at the end 45, constituting the same a rotary forked shaft provided with a slot in which the butt-end of the tube is arranged to be received, as 95 clearly shown in Fig. 5.

Guided pieces 47 are arranged to be received in the guideways 11, 12, and are shown in the form of rollers having annular grooves 48 in which the respective rods 100 of the pairs of guide-rods are received, for guiding said rollers lengthwise of said rods, and maintaining said rollers between the rods of the respective pairs of rods. These rollers are provided with openings 49, 50, 105 for receiving the shanks or fork of the squeezer.

The fork of the squeezer is arranged to be received endwise through one of the rollers and at the respective sides of the butt-end of the tube, and then into the other roller, for locating said butt-end between the

shanks and between said rollers, so that, upon rotation of the squeezer, the flexible metal of the tube will be rolled or wrapped about the rotary squeezer, for causing the 5 squeezing on the tube and the exuding of the contents of the tube through the mouth of the tube.

The supporting plate 17 is provided with extensions 51 for forming slots 52, in which 10 tooth-brushes 53 are arranged to be received, for hanging therein, so as to locate the tooth-brushes conveniently with relation to the paste-tube. A cup 55 is shown located above the supporting plate, and is arranged to receive a drinking glass 56.

The guides are shown as supported by a bracket 57. The guides, the supporting plate, the bracket and the cup are suitably rigidly secured together, which may be accomplished by connecting the guides with the supporting plate in the manner hereinbefore described by the rivets 18, connecting the supporting plate and the cup by rivets 58, and connecting the bracket and the cup by rivets 59.

The location of the cup places the drinking glass in a convenient position for having the upper ends of the tooth-brushes arranged thereabout in convenient manner, for assembling the articles employed in the care of the teeth in close and convenient relation.

When it is desired to use some of the paste in the tube, the cap 27 is unscrewed, and the squeezer 41 is rotated just sufficiently to cause the exuding of sufficient paste from the mouth of the tube for the purpose desired. If the paste is tooth-paste, the tooth-brush may be held immediately under the mouth of the tube, so that the paste will 40 lodge upon the bristles of the tooth-brush, the paste being cut by wiping the brush across the mouth of the paste-tube when sufficient paste has been lodged upon the brush, the cap being then again screwed upon the threaded neck.

Our improved device is of simple construction, and forms convenient means by which the proper amount of paste may be exuded by the individual using the same, in ready manner, and without waste of paste, and in such manner that the paste being used and that remaining in the tubes is always in clean and sanitary condition.

It also provides ready and convenient and

compact means whereby the tube of paste 55 is always ready in convenient position for use and readily accessible to the user.

Having thus fully described our invention, what we claim as new, and desire to secure by Letters Patent, is:

1. In a sanitary paste dispensing device, the combination of a pair of spaced-apart guideways having opposed guiding walls, rollers between said guiding walls, said rollers provided with openings in axial alinement, a support at the lower ends of said guideways for the dispensing end of a paste-tube, a rotary squeezer comprising a pair of shanks having a slot therebetween open at one end, and a handle at the other end of said shanks, said shanks at the open end of said slot arranged to be received endwise through said openings in said rollers and about the butt-end of the paste-tube whereby said butt-end is held between said shanks and arranged in rotative relation between said shanks and between said rollers, and whereby the rotation of said handle causes squeezing of said tube and movement of said rollers lengthwise of said guiding walls.

2. In a sanitary paste dispensing device, the combination of a pair of guideways, each comprising a pair of rods, a supporting bracket for said rods, a plate connecting the lower ends of said rods, said plate provided with a central opening for the mouth of a paste-tube and with a supporting wall for said paste-tube about said opening, rollers guided between the rods of said respective pairs of rods, said rollers provided with openings, a rotary squeezer comprising a pair of shanks having a slot therebetween open at one end, and a handle at the other end of said shanks, said shanks at the open end of said slot arranged to be received through said rollers and about the butt-end of the paste-tube whereby said butt-end is arranged in rotative relation between said shanks and between said rollers, and whereby the rotation of said handle causes squeezing of said tube and movement of said rollers lengthwise of said rods.

In testimony whereof, we have hereunto signed our names.

WILLIAM B. FOSTER.
THOS. E. MANNING.
